US0D1097795S

(12) **United States Design Patent** (10) **Patent No.:** **US D1,097,795 S**
(45) **Date of Patent:** **** Oct. 14, 2025**

(54) **MULTIPLE LEG FRAME JOINER**

(71) Applicant: **Silverside Holdings Pty Ltd.**, Kyneton (AU)

(72) Inventor: **Peter Davis**, Kyneton (AU)

(73) Assignee: **Silverside Holdings Pty Ltd.**, Kyneton (AU)

(**) Term: **15 Years**

(21) Appl. No.: **29/787,665**

(22) Filed: **Jun. 8, 2021**

FIG. 1 is a top view of the multiple leg frame joiner;
FIG. 2 is a front view of the multiple leg frame joiner;
FIG. 3 is a bottom view of the multiple leg frame joiner;
FIG. 4 is a left side view of the multiple leg frame joiner;
FIG. 5 is a right side view of the multiple leg frame joiner;
FIG. 6 is a top isometric view of the multiple leg frame joiner from above; and,

FIG. 7 is a bottom isometric view of the multiple leg frame joiner from below.

The broken lines in the drawings illustrate portions of the multiple leg frame joiner and form no part of the claimed design.
